UNITED STATES PATENT OFFICE.

JOHN CHARLES WILLIAM STANLEY, OF LONDON, ENGLAND.

APPARATUS FOR BLEACHING OLEAGINOUS MATTERS.

SPECIFICATION forming part of Letters Patent No. 681,274, dated August 27, 1901.

Application filed February 26, 1901. Serial No. 48,836. (No model.)

To all whom it may concern:

Be it known that I, JOHN CHARLES WILLIAM STANLEY, a subject of the King of England, residing at London, England, have invented 5 certain new and useful Improvements in Apparatus for Bleaching Oleaginous Matters, of which the following is a specification.

This invention relates to apparatus for bleaching "oleaginous matter," by which 10 term I intend to include all vegetable, fish, and animal oils and greases, and the apparatus may also be employed to bleach waxes.

The object of the invention is to provide an 15 apparatus in which the oleaginous matter or melted wax is continuously circulated in a thin film over transparent surfaces, and thereby subjected to the action of light until the bleaching is accomplished.

The invention also contemplates in some 20 cases the subjecting of the films of certain oils while flowing over the transparent surfaces to the action of air under pressure for a purpose to be hereinafter fully described.

The process of bleaching by my apparatus 25 may be carried on continuously day and night, it being intended to use artificial light whenever necessary.

The process which this apparatus is 30 designed to carry out forms the subject-matter of another application filed by me July 28, 1900, Serial No. 25,175.

The invention will be fully described hereinafter, reference being had to the accompanying drawings, in which—

35 Figure 1 is a sectional elevation of an apparatus constructed in accordance with my invention. Fig. 2 is a horizontal section on the line 2 of Fig. 1. Fig. 3 is a detail view of a fan-tail distributor. Fig. 4 is a sectional detail, on enlarged scale, showing the means for discharging water against the outer face of the transparent surfaces and a modified form of distributor for the oleaginous matter.

Upon a suitable frame *a* is supported a 45 tank *A*, such tank being conical or tapering with its smaller end downward and closed at its lower end. Preferably, also, it will be provided with a top cover *b* in order to exclude foreign substances from the oleaginous 50 matter while being bleached. Upon the cover *b* are supported one or more bleaching-chambers *C*, three being shown; but more or less

may be employed. These chambers are preferably polygonal in horizontal section and each is formed of a series of vertical posts 10, 55 which are grooved longitudinally, as indicated at 11, to receive panes of glass or other transparent material 12. The posts will be connected together at their upper and lower ends by frames 13 and a cover 14 will fit over 60 the top air-tight. The lower ends of the chambers *C* may also be provided with air-tight covers or, as shown, the lower frames 13 may rest directly upon the cover *b* of the tank; but in the latter case provision must 65 be made to insure fluid-tight joints between such frames and the cover *b*.

Above the bleaching-chambers *C* a tank *D* is supported, and this tank *D* is connected to the tank *A* by a pipe *f*, a pump *F* being interposed in such pipe for the purpose of pumping the oleaginous matter from the tank *A* to the tank *D*. Each of the bleaching-chambers is provided with an interior pipe or trough *G*, which extends around the chamber just below the top cover, and a series of pipes *g* lead from the tank *D* through the covers 14 to discharge into said troughs. Each pipe *g* is provided with a cock 15, and the pipes will be so arranged as to distribute the oleaginous matter to all parts of the pipes or troughs *G*, and the amount supplied may be regulated by the cocks 15. A series of fantail distributors 16 may be connected to the pipe or trough *G*, as shown in Figs. 1 and 3, or if a pipe is employed it may be provided with a series of openings or slots 17, as shown in Fig. 4, for the purpose of discharging the oleaginous matter in thin films against the inner vertical surfaces of the bleaching-chambers. 90

In order to return the oleaginous matter from the bleaching-chambers to the tank *A*, I provide each chamber with a plurality of pipes *h*, which are supported by the cover *b* in a fluid-tight manner and project a short 95 distance into said chambers and the tank. Each pipe *h* is provided with a valve *h'*, the stem of which will extend through the side of the tank in order that such valves may be operated from the outside. The intention is 100 to so control the discharge of oleaginous matter from the bleaching-chambers that the upper ends of the pipes *h* may, during the bleaching operation, be below a body of such

oleaginous matter in the lower ends of the bleaching-chambers. Other valved pipes *k* may also be provided, whose upper ends will be flush with the bottom of the chambers *C*, so as to discharge all the oleaginous matter into the tank *A*.

Within each chamber *C* a series of arc-lights *L* will be supported. The power of such lights may be varied; but in a chamber 10 the sides of which have a superficial area of about four hundred square feet three arc-lights of about fifteen-hundred-candle power each, or a number of incandescent lights of a total equivalent candle-power, will bleach 15 the oleaginous matter caused to flow in thin films over the walls of such chamber in a satisfactory manner in from five to eight hours. The length of time will vary according to the nature of the oil or fat being treated.

20 In order to keep the oleaginous matter in a fluid condition for free circulation, I provide the tank *A* with a coil *M*, through which a heating medium, as steam, may be circulated. The inlet end of the coil will have a 25 cock *m*, and its discharge end may lead to a vessel *m'*. Sometimes also when oil is being bleached it may be desirable in order to cool the oil to circulate cold water through the coil. This coil may also be used for the 30 circulation of a refrigerating fluid for the purpose of separating the stearin and other products.

When certain oils, such as linseed-oil, are being bleached, it will sometimes be desirable to improve the drying qualities of such 35 oils, and in order to accomplish this I provide a pipe *N*, through which air under pressure may be forced, and such pipe is provided with branches *n*, which discharge into the 40 bleaching-chambers *C*. At the top of each chamber is a discharge-pipe *O*, provided with a weighted valve *o*, which may be adjusted to maintain the air-pressure within the chambers at any desired degree. As the income 45 of air will be continuous there will be practically a circulation of air under pressure through the bleaching-chambers.

Sometimes the heat from the electric lights 50 may heat the transparent surfaces of the chambers to an excessive degree, and it is necessary, therefore, to provide means to cool them. This may be accomplished by providing pipes *P*, extending around the upper ends of the bleaching-chambers and supplying such pipes with cold water in any suitable manner not necessary to illustrate specifically. Such pipes will be provided with slots or perforations *p*, through which the water will be discharged against the outer 55 sides of the transparent surfaces and flow down them into troughs *q*, at the lower ends of the chambers.

If desired, the entire apparatus may be enclosed in a glass house, (indicated by *R*.)

55 From the foregoing description it will be evident that the tank *A* may be filled with oleaginous matter and that such matter may

be constantly circulated and caused to flow in thin films over the transparent sides of the bleaching-chamber until the desired degree 70 of bleaching has been attained; also, that the operation may be continuous day and night, natural light supplemented by artificial light, if necessary, being utilized during the day and artificial light during the 75 night. When air is forced into the chambers *C*, the discharge from such chambers to the tank *A* will be through pipes *h*, and when air is not used such discharge may be through the pipes *k*.

80 Without limiting myself to the precise details of construction illustrated and described, I claim—

1. The combination, in an apparatus for bleaching oleaginous matter, of transparent 85 plates, means for conveying the oleaginous matter to said plates to flow in thin films over the plates, and means for directing light through said plates, substantially as described.

90 2. The combination, in an apparatus for bleaching oleaginous matter, of means for varying the temperature of the matter, transparent plates, means for conveying the matter to the plates to flow in thin films over the 95 plates, and means for directing light through said plates, substantially as set forth.

95 3. The combination, in an apparatus for bleaching oleaginous matter, of vertically-supported transparent surfaces, means to 100 discharge the matter on the upper portions of the transparent surfaces in thin films, and means for producing artificial light, in close proximity to such surfaces, substantially as set forth.

105 4. In an apparatus for bleaching oleaginous matter, the combination of a closed chamber having vertical transparent walls, means for conveying the matter to the interior of the chamber to flow in thin films over the transparent walls, and means for producing artificial light within the chamber, substantially as set forth.

110 5. In an apparatus for bleaching oleaginous matter, the combination of a closed chamber 115 having vertical transparent walls, means for conveying the matter to the interior of the chamber to flow in thin films over the transparent walls, means for producing artificial light within the chamber, and means for cooling said transparent walls externally, substantially as set forth.

120 6. In an apparatus for bleaching oleaginous matter, the combination of a closed chamber having vertical transparent walls, means for 125 conveying the matter to the interior of the chamber to flow in thin films over the transparent walls, means for producing artificial light within the chamber, and means for introducing air under pressure into said chamber, substantially as set forth.

130 7. In an apparatus for bleaching oleaginous matter, the combination of a tank to contain the matter to be bleached, transparent plates

supported above the tank, means for conveying the matter from the tank and delivering it to flow in thin films over the transparent surfaces back to the tank, means to vary the 5 temperature of the matter within the tank, and means for directing light through said plates, substantially as set forth.

In testimony whereof I have signed my name to this specification in the presence of two subscribing witnesses.

JOHN CHARLES WILLIAM STANLEY.
